Fitter.

UNITED STATES PATENT OFFICE.

DAVID FREEMAN, OF CHICAGO, ILLINOIS.

POOL-BALL RACK.

Application filed May 7, 1921. Serial No. 467,763.

To all whom it may concern:

Be it known that I, DAVID FREEMAN, a subject of the King of Great Britain, residing at Chicago, in the county of Cook and State of Illinois, have invented new and useful Improvements in Pool-Ball Racks, of which the following is a full, clear, concise, and exact description, reference being had to the accompanying drawing, forming 10 a part of this specification.

This invention relates to improvements in pool ball racks and has for its object the production of a device of this character which will be coin controlled, that is, a device which will be incapable of use except upon the deposit of a coin or coins of predetermined denomination.

A further object is the production of a pool ball rack which will be of simple and economical construction and efficient in use. Other objects will appear hereinafter.

The invention will be best understood by reference to the accompanying drawing, in which—

25 Fig. 1 is a rear view of a pool ball rack embodying the invention, portions of the same being broken away to disclose underlying parts, the barriers at the inlet openings of the rack being shown in depressed or inoperative position;

30 Fig. 2 is an end elevation of the rack showing the inlet or admission openings thereof, the barriers at the inlet openings of the rack being shown in elevated or operative position;

35 Fig. 3 is a detail section cross section view through one of these barriers;

40 Fig. 4 is a detail section taken on substantially line 4—4 of Fig. 3;

45 Fig. 5 is an enlarged detail section illustrating a pivotally mounted stop member at the discharge end of each shelf for holding the balls on the shelves; and

50 Fig. 6 is a detail perspective view showing the means employed for locking the ball barriers in operative position; and

55 Fig. 7 is a detail section through the point of pivotal mounting of one of the ball stops showing the recesses in the ball support for receiving the stop when the latter is rocked to inoperative position.

The preferred form of construction as illustrated in the drawing comprises a rack having a substantially rectangular body 10 in which are provided a plurality of superposed parallel compartments 11 for the pool

balls A. The balls, when arranged in said compartments, rest upon the bottoms 12 of said compartments which form, as will be seen, a plurality of vertically spaced shelves. 60

One end of the body 10 of the rack is provided with inlet openings 13 through which the pool balls may be inserted into the compartments 11. Provided in the bottom of each compartment adjacent the opposite end of the rack is an outlet opening 14, the openings 14 being in vertical alignment so that the balls, in passing through the outlet openings of the upper compartments, will pass through the outlet openings of the compartments below, and be ultimately deposited into a receptacle 15 which is slidably mounted in the lower end of the body 10. Said receptacle 15 is provided at its outer end with a handle or knob 16, 75 whereby the same may be readily inserted or withdrawn.

Provided at each of the inlet openings 13 is a barrier 17, an opening or recess 18 being provided at the lower side of each opening 80 13 for the reception of the barrier cooperating therewith. Each barrier is pivoted at 19 and is normally held in elevated or operative position by means of a helical compression spring 20. Said spring normally holds the barrier against stops 21, and in the downward movement of the barrier to inoperative position the spring will be compressed. When the barrier is in elevated or operative position, the same reduces the size 90 of the corresponding opening 13 to such an extent as to prevent the insertion of a pool ball therethrough.

Cooperating with each barrier is a detent 22 which is pivotally mounted at its lower 95 end as at 23. Each detent 22 is arranged to engage under a laterally projecting lug 24 provided upon the corresponding barrier to lock the latter in elevated or operative position. A leaf spring 25 cooperates with 100 each detent to automatically move the detent into operative relation with the barrier when the latter reaches its elevated or operative position.

Cooperating with each barrier 17 for unlocking the same is a coin controlled mechanism 26, having a suitable coin admission slot 26'. The construction of each mechanism 26 will be such that, upon the insertion of a coin of proper denomination into the 110 coin admission slot 26' thereof, a lever 27 of the mechanism will be unlocked so as to

permit the depression thereof. Upon such depression of said lever 27, a rearwardly projecting arm 28 of the mechanism will be also depressed. The arm 28 is provided with a laterally projecting stud 29, said stud, upon depression of said arm engaging against an inclined surface 30 on the corresponding detent 22, as clearly seen in Fig. 6, so as to move the detent to releasing position and thus unlock the barrier. Continued downward movement of the arm 28 then brings the same into engagement with the lug 24, whereupon the barrier will be swung downwardly to inoperative position so as to permit of the insertion of a pool ball through the corresponding opening 13.

Cooperating with each barrier to hold the same in depressed or inoperative position is a locking bar 31, which is slidably mounted in suitable bearings 32 and 33, as clearly seen in Fig. 1. Cooperating with each bar is a helical tension spring 34 which serves to normally press the bar toward the barrier 17 with which the same cooperates, so that when the barrier reaches its lower terminal of movement upon depression of said barrier, a shoulder 31' on the barrier will have passed the adjacent end of said bar, and the latter, under the influence of the spring 34, cooperating therewith, will move into engagement with said shoulder and thus serve to lock the barrier in depressed position. Thus unlocking of the barrier at each of the inlet openings 13 is governed by the corresponding coin controlled mechanism, so that in the use of the rack the insertion of a ball or balls into any one of the compartments 11, will not be permitted until the proper coin has been inserted into the corresponding coin controlled mechanism.

The end of each bar 31, remote from the barrier cooperating therewith, is bent laterally as at 35 and engages with a slotted link 36 which is pivoted at 37 to a vertically extending bar 38. The bar 38 projects through and is slidably mounted in the bottoms 12 of the compartments 11, all of the links 36 being connected therewith. Provided at the lower end of the bar 38 is a roller 39 which, when the receptacle 15 is in closed position, rests upon the depressed surface 40 thereof, as clearly seen in Fig. 1. Upon opening or outward sliding of said receptacle, the roller 39 will ride up on inclined surface 41 to the elevated surface 42 of said receptacle, thereby causing the bar 38 to be moved upwardly. In this upward movement of said bar the links 36 engaging the ends 35 of the bars 31, will cause the latter to be moved to the right, in the illustration shown in Fig. 1, providing said bars are in engagement with the shoulders 31' of the barriers 17, causing said bars 31

to be retracted from said shoulders 31', thereby releasing the barriers 17 which will be returned to elevated or operative position by the springs 20. The slots provided in the links 36 are elongated so as to allow for relative retrograde movement of said links when the bar 38 again moves downwardly to engagement with the depressed surface 40 upon reinsertion of the receptacle 15. To limit the downward movement of the bar 38 upon complete withdrawal or removal of the receptacle 15, said bar is provided with a stop 43. An inclined surface 44 is provided at the inner end of said receptacle for engagement with the roller 39, upon insertion of said receptacle after complete removal of the same.

The bottoms 12 of compartments 11 are inclined toward the outlet openings 14, so that the balls, upon insertion of the same into said compartments, will roll by gravity toward the outlet openings thereof. In order to arrest the balls so as to prevent immediate discharge of the same through said outlet openings, stops 45 are provided, one of which is arranged adjacent each outlet opening, being pivoted at 46, as clearly seen in Figs. 1 and 5. A helical tension spring 47 cooperates with each stop 45 to normally hold the same in upright or operative position; the rearward end of each spring being connected with a base 47', which extends inwardly from the adjacent wall of the body 10 of the rack. In order to rock the stops 45 to inoperative position, so as to release the balls at the desired time, the bars 31 are provided with projecting arms 48 and 48', the lowermost bar 31 having two members 48 and 48', whereas each of the other bars 31 have but one member 48' projecting upwardly therefrom. The member 48 projects downwardly from the lowermost bar 31 through a slot in the adjacent bottom member 12 for engagement with the lower end of the adjacent stop 45, as clearly seen in Fig. 5. The member 48' projects upwardly from the bar 31 into engagement with the lower end of the stop 45 just above, as also seen in Fig. 5. The arrangement is such that in the movement of the bars 31, which causes retraction of the same from the shoulders 31' of the barriers 17, as above described, the stops 45 will be rocked to horizontal position into recesses 49 provided in the upper and lower sides of bottom members 12, thereby releasing the balls, so as to permit of the same passing on to the outlet openings 14, as will be readily understood. In order that the balls may be viewed while in the rack, the front side of the latter is provided with a glass panel 50, as seen in Fig. 5.

With a device of the construction set forth, then it will be seen that the receptacle 15 will always be unlocked and ready

to be removed to deposit the balls on to the table for play. In order to place the balls in the various compartments or shelves of the rack as the balls are knocked into the 5 pockets of the table, during play, it becomes necessary to deposit a coin of the required denomination into the coin controlled mechanism of each of the compartments or shelves used. In other words, a coin will 10 have to be deposited by each player in order to secure a shelf or compartment in the rack to accommodate the balls which are secured by the player during the play. In the deposit of a coin by a player, the barrier 15 of the corresponding compartment or shelf will be released and moved to inoperative position, upon depression of the lever 27 by the player. The balls will be inserted into the various compartments or 20 shelves of the rack by the various players and upon completion of the game, the receptacle 15 may be withdrawn to deposit the balls on the table for another game. In the withdrawal of the receptacle, however, 25 the rod 38 will be moved upwardly, causing the bars 31 to be retracted, thus releasing the barriers 17 which will be returned to elevated or operative position by the springs 20. At the same time the members 30 48 and 48' of the bars 31 will engage with and rock the stops 45 to inoperative position, thus releasing the balls and permitting the same to pass to the discharge openings 14, whence the same will pass downwardly 35 into the receptacle 15, so that before the latter is completely withdrawn, all of the balls will have been deposited therein.

With this arrangement, it will be seen that the use of the rack will be coin controlled, 40 it being necessary for each player in the playing of each game to deposit a coin in order to secure the use of a compartment or shelf for the deposit of his balls.

With this arrangement the services of 45 attendants in pool rooms may be dispensed with or materially reduced, and the time ordinarily consumed by an attendant in caring for the balls before successive games, that is "spotting" the balls on the table, will 50 be saved.

While I have illustrated and described the preferred form of construction for carrying out my invention, this is capable 55 of variation and modification without departing from the spirit of my invention. I, therefore, do not wish to be limited to the precise details of construction set forth, but desire to avail myself of such variations and modifications as come within the scope 60 of the appended claims.

What I claim as new, and desire to secure by Letters Patent is:

1. In a device of the class described, a 65 supporting element for balls, a barrier pivotally mounted in said element at one end

thereof, means adjacent said supporting element for locking said barrier in a position preventing the insertion of balls into said element, and coin controlled mechanism for temporarily disabling said locking element. 70

2. In a device of the class described, a plurality of supporting elements for balls, barriers pivotally mounted in the ends of said elements, locking means adjacent each supporting element for locking said barriers in 75 a position preventing the insertion of balls into said elements, and coin controlled mechanisms for temporarily disabling said locking means, said mechanisms each being provided with a member for displacing the 80 locking means adjacent each supporting element.

3. In a device of the class described, a plurality of supporting elements for balls, a vertically movable barrier at the intake end 85 of each supporting element, a locking member for each barrier, and a coin controlled mechanism for each locking member for temporarily disabling the locking member to permit the insertion of balls into said 90 supporting element.

4. In a device of the class described, a supporting element for balls, a barrier movable in the intake end of said supporting element to prevent the insertion of balls, a 95 locking member mounted adjacent said barrier to lock the same in position, and coin controlled mechanism provided with a member for disabling said locking means.

5. In a device of the class described, a 100 supporting element for balls, said element having an inlet and an outlet opening, a barrier adjacent said inlet opening for preventing the insertion of balls into said supporting element, locking means for said barrier, coin controlled mechanism for temporarily disabling said locking means, means 105 for holding said barrier in non-locking position when said locking means is disabled, means for arresting the balls to prevent passage thereof into said outlet opening, said barrier holding means cooperating with said ball arresting means whereby said barrier moves to locking position upon the removal of said ball arresting means. 110

6. In a device of the class described, a supporting element for balls, said element having inlet and outlet openings for the balls; a barrier for preventing insertion of balls through said inlet opening; coin controlled mechanism for locking said barrier in operative position; a lock for holding said barrier in inoperative position; a stop for arresting the balls to prevent passage of the same into said outlet opening; means for moving said stop to inoperative position and for actuating said lock to release said barrier; and means for moving said barrier to operative position when said barrier is released. 120 125 130

7. In a device of the class described, a supporting element for balls, said element having inlet and outlet openings for the balls; a barrier for preventing insertion of 5 balls through said inlet opening; coin controlled mechanism for locking said barrier in operative position; a lock for holding said barrier in inoperative position; a stop for arresting the balls to prevent passage of 10 the same into said outlet opening; means for simultaneously moving said stop to inoperative position and for actuating said lock to release said barrier; and means for moving said barrier to operative position when 15 said barrier is released.

8. In a device of the class described, a supporting element for balls, said element having inlet and outlet openings for the balls; a barrier for preventing insertion of 20 balls through said inlet opening; coin controlled mechanism for locking said barrier in operative position; a lock for holding said barrier in inoperative position; a stop for arresting the balls to prevent passage of the 25 same into said outlet opening; a movably mounted receptacle for balls when discharged through said outlet opening; means for utilizing the movement of said receptacle to actuate said stop and lock; and means for moving said barrier to operative position when said barrier is released.

9. In a device of the class described, a supporting element for balls, said element having inlet and outlet openings for the 35 balls; a barrier for preventing insertion of balls through said inlet opening; coin controlled mechanism for locking said barrier in operative position; a lock for holding said barrier in inoperative position; a stop for arresting the balls to prevent passage of the same into said outlet opening; a slidably mounted receptacle for the balls when discharged through said outlet opening; means for utilizing the sliding movement of said 40 receptacle to actuate said stop and lock; and means for moving said barrier to operative position when said barrier is released.

10. In a device of the class described, a supporting element for balls, said element 50 having inlet and outlet openings for the balls; a barrier for preventing insertion of balls through said inlet opening; coin controlled mechanism for locking said barrier in operative position; a lock for holding 55 said barrier in inoperative position; a stop for arresting the balls to prevent passage of the same into said outlet opening; a movably mounted receptacle for the balls when discharged through said opening; means for 60 utilizing the movement of said receptacle to actuate said stop and lock whereby, upon outward movement of said receptacle, said stop will be moved to inoperative position and said lock will be actuated to release said 65 barrier; and means for moving the said barrier to operative position when said barrier is released.

11. In a device of the class described, a plurality of superposed supporting elements for balls, each of said elements having an inlet and an outlet opening for the balls; barriers cooperating with said inlet openings for preventing insertion of balls therethrough; coin controlled mechanism cooperating with each barrier for locking the same in operative position; locks for holding said barriers in inoperative position; stops cooperating with said outlet openings for arresting the balls to prevent passage of the same thereinto; a movably mounted receptacle for the balls when discharged through said outlet openings; means for utilizing the movement of said receptacle to actuate said stops and locks; and means for moving said barriers to operative position when released.

12. In a device of the class described, a plurality of superposed supporting elements for balls, each of said elements having an inlet and an outlet opening for the balls; barriers cooperating with said inlet openings for preventing insertion of balls therethrough; coin controlled mechanism cooperating with each barrier for locking the same in operative position; locks for holding said barriers in inoperative position; stops cooperating with said outlet openings for arresting the balls to prevent passage of the same thereinto; a movably mounted receptacle for the balls when discharged through said outlet openings; means for utilizing the movement of said receptacle to actuate said stops and locks; and means for moving said barriers to operative position when released.

13. In a device of the class described, a plurality of superposed supporting elements for balls, each of said elements having an inlet and an outlet opening for the balls; barriers cooperating with said inlet openings for preventing insertion of balls therethrough; coin controlled mechanism cooperating with each barrier for locking the same in operative position; locks for holding said barriers in inoperative position; stops cooperating with said outlet openings for arresting the balls to prevent passage of the same thereinto; a slidably mounted receptacle for the balls when discharged through said outlet openings; means for utilizing the movement of said receptacle to actuate said stops and locks, whereby, upon outward movement of said receptacle, said stops will be moved to inoperative position and said locks will be retracted to release said barriers; and means for moving said barriers to operative position when released.

14. In a device of the class described, a plurality of superposed supporting elements for balls, each of said elements having an inlet and an outlet opening for the balls; barriers cooperating with said inlet openings for preventing insertion of balls therethrough; coin controlled mechanism cooperating with each barrier for locking the same in operative position; locks for holding said barriers in inoperative position; stops cooperating with said outlet openings for arresting the balls to prevent passage of the same thereinto; a slidably mounted receptacle for the balls when discharged through said outlet openings; means for utilizing the movement of said receptacle to actuate said stops and locks, whereby, upon outward movement of said receptacle, said stops will be moved to inoperative position and said locks will be retracted to release said barriers; and, upon return of said receptacle to operative position, said stops will be moved to operative position and said locks will be retracted to release said barriers.

will again assume operative position; and means for moving said barriers to operative position when released.

14. In combination, a plurality of substantially closed shelves for carrying articles thereon, said shelves having openings for the insertion of said articles and a common discharge for the removal of the articles, and mechanism including a plurality of barrier members and cooperating devices associated with said common discharge for automatically blocking the insertion of the articles through said openings after the articles have been removed from said shelves by way of said common discharge.

15. In combination, a pool ball rack comprising one or more shelves for receiving balls, each shelf being provided with an inlet opening and an outlet opening, barrier, means adjacent to each of said openings adapted when in operative position to prevent the entrance and the removal of the balls from each shelf, and mechanism cooperating with said barrier means adjacent both openings of each shelf for releasing each of said means, said mechanism functioning to release and move to inoperative position one of said means while the other said means is held in operative position.

16. In combination, a pool ball rack comprising one or more shelves for receiving balls, each shelf being provided with an inlet opening and an outlet opening, a barrier at said inlet opening adapted when in operative position to prevent the insertion of the balls, a stop adjacent to said outlet opening adapted when in operative position to prevent the removal of the balls, and mechanism connected to said barrier and said stop for actuating said barrier and said stop to move them alternatively to operative positions.

17. In combination, a pool ball rack comprising one or more shelves for receiving balls, each shelf being provided with an inlet opening and an outlet opening, a barrier at said inlet opening adapted when in operative position to prevent the insertion of the balls, a stop adjacent to said outlet opening adapted when in operative position to prevent the removal of the balls but to be in inoperative position when said barrier is in operative position, interconnecting means between said barrier and said stop for accomplishing such movement of said barrier and said stop, and means for actuating said interconnecting means.

18. In combination, a pool ball rack comprising one or more shelves for receiving balls, each shelf being provided with an inlet opening and an outlet opening, a barrier at said inlet opening adapted when in operative position to prevent the insertion of the balls, a stop adjacent to said outlet

opening adapted when in operative position to prevent the removal of the balls, an interconnecting rod for moving said stop to inoperative position and for simultaneously releasing said barrier to permit it to move to operative position, and mechanism for actuating said interconnecting rod.

19. In combination, a pool ball rack comprising one or more shelves for receiving balls, each shelf being provided with an inlet opening and an outlet opening, a barrier at said inlet opening adapted when in operative position to prevent the insertion of the balls, a stop adjacent to said outlet opening adapted when in operative position to prevent the removal of the balls, mechanism adjacent to said outlet opening and cooperating with said barrier and said stop for simultaneously moving them into operative and inoperative positions respectively, and coin controlled mechanism adjacent to said inlet opening for releasing said barrier after moved into operative position.

20. In combination, a pool ball rack comprising one or more shelves for receiving balls, each shelf having an opening for receiving the balls, a barrier cooperating with said opening for preventing the insertion of the balls while in non-retracted position, means including a token receptacle for actuating said barrier to retracted position upon the insertion of a token in the receptacle whereupon the balls may be inserted through said opening, a stop at the opposite end of said shelves for holding the balls on the shelves, means for displacing said stop to discharge the balls from said shelves, and interconnecting means for returning said barrier to non-retracted position upon the displacement of said stop.

21. In combination, a pool ball rack comprising shelves for receiving balls, said shelves having inlet openings for receiving the balls, barrier movable into and out of said inlet openings, a discharge trough for receiving the balls from said shelves, and mechanism cooperating with said barriers and said trough to prevent the insertion of balls through said inlet openings after the trough has been removed from the rack.

22. In combination, a pool ball rack comprising shelves for receiving balls, said shelves having inlet openings for receiving the balls, barriers movable into and out of said inlet openings, a discharge trough for receiving the balls from said shelves, mechanism cooperating with said barriers and said trough to prevent the insertion of balls through said inlet openings after the trough has been removed from the rack, and coin controlled mechanism for rendering said barriers inoperative to permit the insertion of the balls through said openings.

23. In combination, a pool ball rack comprising one or more shelves for receiving

6
balls, each shelf being provided with an inlet opening and an outlet opening, said outlet openings discharging said balls to a common trough, and mechanism including a plurality of barriers cooperating with said trough whereby said inlet openings are blocked against the reception of balls when said trough is removed.

24. In combination, a pool ball rack comprising one or more shelves for receiving balls, each shelf being provided with an inlet opening and an outlet opening, said outlet

openings discharging said balls to a common trough, mechanism including a plurality of barriers cooperating with said trough whereby said inlet openings are blocked against the reception of balls when said trough is removed, and token receiving means for rendering said mechanism ineffective to allow insertion of balls through said inlet openings.

In witness whereof, I have hereunto subscribed my name.

DAVID FREEMAN.
